(57) **CLAIM**

The ornamental design for a D-grip for tool, as shown.

DESCRIPTION

FIG. 1 is an isometric view of the D-grip and showing a tool handle in phantom.

FIG. 2 is a top view of the D-grip.

FIG. 3 is a bottom view of the D-grip.

FIG. 4 is a first end view of the D-grip.

FIG. 5 is a second end view of the D-grip.

FIG. 6 is a left side view of the D-grip; and,

FIG. 7 is a right side view of the D-grip.

The broken line showing of the D-grip for tool is included for the purpose of illustrating portions of the article and forms no part of the claimed design.
